Gibney

Design for silver Forks and
Patented Dec 11, 1844.

FIG. 1

FIG. 2.

Dec. 26

Michael Gibney, City & State of New York
Letters Patent No. 26, dated Dec 4, 1844

The Schedule referred to in these Letters Patent and making part
of the same. —

Specification of a new and improved Design to be em-
bossed upon articles of silver manufacture by Michael Gibney
To all whom it may concern. —

Be it known that I Michael Gibney of No. 1. Trinity
Place, in the City and State of New York, have invented or
produced a new Design to be embossed upon the follow-
ing articles of silver manufacture viz: Forks, Spoons, Ladles,
Butter Knives, Serrated Knives & Fish Knives, and I do
hereby declare that the following is a full and exact des-
cription of the same. Reference being had to the annexed
drawings making a part of this specification in which fig. 1.
is the front view and fig. 2. the back view of a fork,
which is one of the articles before named and which is
here given to exhibit the positions for the new design
to be placed upon each of the said articles. —

The design is of the Louis 14th style of art. consisting
principally of two foliate stems forming a border to the back
and front parts of the upper portion of the handles of the said
articles of silver manufacture as shown upon drawings
at B.B. fig. 1. and B.B. fig. 2. The lower portion of the
handles of the said articles of silver manufacture consists
of three elongated leaves terminating at the lower end with
scrolls as shown at C.C. fig. 1. and C.C. fig. 2.

What I claim and wish to secure by Letters Patent
is the application of the Design, which I have described

2

Des. 26

drawings) by means of embossing it upon the following
articles of silver manufacture viz Forks, Spoons, Ladles,
Butter Knives, Saffron Knives and Fish knives.
